Attorney

Patented July 1, 1924.

UNITED STATES PATENT OFFICE.

AUGUST FRANCONETTI, OF WASHINGTON, DISTRICT OF COLUMBIA.

GEM-SEAT-GROOVING TOOL.

Application filed September 27, 1922. Serial No. 590,912.

To all whom it may concern:

Be it known that I, AUGUST FRANCONETTI, a citizen of the United States, residing at Washington, District of Columbia, have invented certain new and useful Improvements in Gem-Seat-Grooving Tools, of which the following is a specification.

This invention relates to improvements in devices for forming gem seating grooves in rings and other jewelry where the stones are set in openings other than round openings, although the device is likewise adapted for use in grooving round openings for the reception of stones.

Jewelers experience considerable difficulty in setting oval, square and irregular cuts, due to the fact that the groove upon which the stone must seat in the setting must be cut by hand, causing the groove to be often irregular and resulting in many instances in settings which are not as perfect as they should be. For this reason, the setting of odd shaped gems is usually comparatively costly. This invention provides means whereby the groove of such irregular openings may be cut to a uniform depth both as regards the size of the groove and the spacing of the gem seat from the face of the setting in which the gem is to be placed.

A still further object of the invention is to provide a device of this character which may be very cheaply produced and readily operated, and in the use of which no special tools or accessories are required.

These and other objects I attain by the construction and arrangement shown in the accompanying drawings wherein for the purpose of illustration is shown a preferred embodiment of my invention and wherein like reference characters designate like parts throughout.

In the drawings:—

Figure 1 is a side elevation partially in section showing a device constructed in accordance with my invention in use for forming a gem seating groove in a ring set opening;

Figure 2 is a section on the line 2—2 of Figure 1;

Figure 3 is a sectional view taken through the shaft showing one manner of mounting the burr therein, and

Figure 4 is a modified form of burr.

Referring now more particularly to the drawings, the numeral 10 indicates a shaft

adapted for engagement in a jeweler's lathe and having formed thereon at a point spaced from the end, or secured thereto as desired, an abutment member or collar 11. The end 60 of the shaft has either formed thereon or secured thereto a cutter or burr 12, in Figure 1 this burr being shown as formed integrally with the shaft and in Figure 3 being illustrated as provided with a shank 65 13 inserted in a bore formed in the end of the shaft. This cutter is in the form of two cones having their bases disposed against one another, the outer faces of these cones being provided with teeth, one of the 70 cones being secured either to the shaft 10 or shank 13 as the case may be. If desired, a cutter such as shown in Figure 4 may be employed wherein the teeth are formed only on the outer cone of the cutter head. 75

The numeral 14 designates a member slidably and rotatably mounted upon the end of the shaft 10 in which the cutter 12 is mounted, and adapted to abut against the collar 11. This member has formed thereon 80 a flange 15 which, when the member abuts the collar 11, is flush with the end of the shaft 10, this flange being of considerable size and forming a rest against which the face of the setting in which the gem receiving opening is formed is placed. That face of the flange next adjacent the burr is highly polished so that the flange if rotated through the rotation of the shaft 10 will not exercise a twisting effect upon the 85 jewelry held thereagainst and will not mar the same. With the shaft 10 placed in a jeweler's lathe and rotated, the jewelry in which the seat is to be formed is placed against the flange 15 and moved against the 90 cutter 12 so that the teeth thereof engage in the side wall of the gem receiving opening 16 and a groove 17 is formed therein. The groove may be regulated as regards its distance from the face through which 100 the setting is to be exposed by means of washers 18 or the like placed between the member 14 and the collar 11 to adjust the member 14 longitudinally of the shaft 10.

It has been found in practice that with a structure as above recited, odd shaped stone receiving openings may be readily grooved and in a very short space of time when compared with the ordinary hand operation. It will be obvious that by varying 110 the shape of the cutter or burr 12, the character of the groove may likewise be altered

to suit the requirements of the work at hand, and I do not accordingly wish to limit myself to the specific construction of the burr or to the specific structure above recited except as hereinafter claimed.

I claim:—

1. In a device for forming grooves in the walls of gem receiving openings of jewelry comprising a rotatable shaft, a burr carried by the end of the shaft, and a flange carried by the shaft and adapted for engagement by it of jewelry in which the grooves are to be formed, said flange being adjustable longitudinally of the shaft.
- 10 2. In a device for forming grooves in the walls of gem receiving openings of jewelry comprising a rotatable shaft, a burr carried by the end of the shaft, and a flange carried by the shaft and adapted for engagement by it of jewelry in which the grooves are to be formed, said flange being adjustable longitudinally of the shaft, said shaft being rotatable in said flange.
- 15 3. In combination with a burr chucking

shaft for jewelers' lathes and the like and a burr carried thereby, a stop element carried by the shaft at a point spaced from the burr receiving end thereof, a member mounted on the shaft and abutting the stop member, a flange formed on the opposite end of the member and having that face thereof next adjacent the burr highly polished.

4. In combination with a burr chucking shaft for jewelers' lathes and the like and a burr carried thereby, a stop element carried by the shaft at a point spaced from the burr receiving end thereof, a member mounted on the shaft and abutting the stop member, a flange formed on the opposite end of the member and having that face thereof next adjacent the burr highly polished, and means insertible intermediate the first named end of the member and the stop element for adjusting the member longitudinally of the shaft.

45 In testimony whereof I affix my signature.

AUGUST FRANCONETTI.
